UNITED STATES PATENT OFFICE.

FRIEDRICH OBERHÄNSLI, OF KESSWIL, SWITZERLAND.

VAPORIZER FOR INTERNAL-COMBUSTION MOTORS.

No. 892,296.

Specification of Letters Patent.

Patented June 30, 1908.

Application filed August 15, 1907. Serial No. 388,661.

To all whom it may concern:

Be it known that I, FRIEDRICH OBERHÄNSLI, a citizen of Switzerland, residing at Kesswil-on-the-Bodensee, in the Republic of Switzerland, have invented certain new and useful Improvements in and Relating to Improvements in Vaporizers for Internal-Combustion Motors, of which the following is a specification.

10 The invention has reference to vaporizers for internal combustion motors, for liquid fuel, in which the fuel is converted into a gaseous condition by means of a vaporizer placed before the cylinder head, and the invention relates more particularly to the employment of a high compression for the air of combustion, in order to obtain as complete a combustion as possible. In machines of this kind as hitherto constructed, premature 15 ignitions frequently take place when the air at high pressure passes into the heated vaporizer, and various means, such as water sprays are adopted for preventing such premature ignition. All these methods present numerous 20 defects and are not always reliable, so that frequently the object sought is not attained.

In the internal combustion motor, an obturating member is arranged in the known 25 manner in the passage connecting the vaporizer with the cylinder head, and in accordance with the present invention this member is slowly closed during the suction of the air so that at the beginning of the compression 30 period the combustion chamber is divided into two compartments entirely separate one from the other. In one of the compartments, in the cylinder, there is practically only pure air, as only a very small quantity of fuel in a 35 finely divided condition is contained therein, that is to say the small quantity which reached the cylinder during the short time during which the obturating member in the 40 passage connecting the vaporizer and the cylinder was open. In the second compartment, in the vaporizer, only fuel is present 45 which has been vaporized.

At the end of the compression period, communication between the vaporizer and the 50 cylinder is established by opening the obturating member arranged on the connecting passage, whereupon the combustion of the hot fuel takes place almost instantly that is as soon as it is subjected to the influence of 55 the high pressure air.

In order to hasten the combustion by in-

timately mixing the fuel with the air, before the vaporizer is placed in communication with the cylinder a portion of the high pressure air is admitted to the vaporizer, and expels 60 the fuel from the vaporizer towards the cylinder head, at the proper time an intimate mixing of the fuel with the air contained in the cylinder being produced.

The object of the invention is illustrated 65 by way of example in the accompanying drawing, in which:

Figure 1 represents a longitudinal section through the cylinder head on the line A—A of Fig. 3. Fig. 2 represents a longitudinal 70 section on the line B—B of Fig. 3. Fig. 3 is a view of the cylinder head and Fig. 4 represents a section on the line C—C of Fig. 3.

The engine, which as a whole follows the known construction, comprises the air admission valve *a* and the exhaust valve *b* in the cylinder head, which latter carries the vaporizer *d* communicating with the cylinder through a relatively narrow passage *c*. The nozzle *e* supplying the combustible and 80 a valve *f* are arranged in the vaporizer wall; this valve obturates a passage *g* in the direction of the vaporizer. A rotary valve *h* or other appropriate obturating member is inserted in the narrow passage *c* connecting 85 the vaporizer with the cylinder. The rotary valve presents two passages, a large passage, *i* corresponding to the passage *c* and a passage *j* of smaller cross section. This latter passage corresponds to a passage *k* formed in 90 the cylinder head and leading into a passage *l* running perpendicularly to the axis of the rotary valve (Fig. 4) and which communicates with the passage *g* leading to the vaporizer *d* by means of a pipe *m*. The passages 95 *i*, *j* are arranged relatively one to the other in such a manner that after the obturation of the connecting passage *c* between the vaporizer and the cylinder a slight rotation in the same direction is necessary in order to set the rotary valve in such a manner that the passage *j* comes opposite the passage *k*.

The vaporizer *d* is surrounded by a cooling jacket *o* closed by means of a cover *p* and receiving cooling liquid in order to prevent excessive heating of the vaporizer. The covers *p* also serve to give access to the vaporizer for heating the same before the engine is started.

The operation of my device is as follows:— 110 At the beginning of the suction period, the rotary valve *h* is adjusted in such a manner

that the vaporizer and the cylinder are connected one with the other. During the suction, fuel is forced to the vaporizer by any suitable means, for example a pump, through the nozzle *e* and air enters the cylinder through the air admission valve *a*. During the suction period the rotary valve *h* is slowly turned in the obturating direction, so that at the end of the suction period the combustion chamber is divided into two compartments entirely separated from each other, one forming the vaporizer and the other the cylinder. During the suction period only so much fuel reaches the cylinder as is necessary for slightly enriching the air, and thereby facilitating the subsequent combustion of the fuel, without however affording the possibility of premature ignition.

In the compression period, the almost pure air is alone compressed, so that the pressure of permissible compression is very high, as premature ignitions are impossible owing to the closing of the vaporizer. Before the end of the compression period the rotary valve is turned by means of the rod *W*, joined to any suitable reciprocating part of the engine (not shown) until its bore *j*, registers with the passage *k*, (see Fig. 4) while the passage *c*, connecting the vaporizer and the cylinder remains closed. This passage *k*, connects with the passage *l*, and pipe *m*, as shown, and the latter connects with the vaporizer *d*, through the passage *g*, and valve *f*, as best seen in Fig. 2, all as above disclosed. The said passages *k*, *l* and *m*, being restricted, a part of the compressed air from the cylinder flows through the same and the valve *f*, into the vaporizer before the end of the compression period; where it expands, mixes with the fuel in the vaporizer *d*, and increases the pressure in said vaporizer. Immediately following the opening of the passage *k*, the valve *h*, is so rotated as to close said passage and to open the passage *c*, and thereby open direct communication through the latter between the said vaporizer and said cylinder. This communication is established at, or an instant before, the end of the compression period, and air, therefore, at a high pressure flows from the cylinder into the vaporizer in opposition to the mixture of air and fuel which was formed in the vaporizer at a lower pressure, and forces a portion of said mixture to flow out of said vaporizer and into said cylinder, thereby causing both cylinder and vaporizer to be filled with air and fuel, and an almost instantaneous combustion to take place.

Air at high pressure remains in the pipe *m* after its connection with the vaporizer until the pressure beneath the valve *f* becomes smaller than the pressure of the air in the pipe *m*. This is the case at the end of the expansion, and during the exhaust. The air then passes from the pipe *m* into the

vaporizer and flushes this latter, as the combustion residues are forced into the cylinder, thereby preventing fouling of the vaporizer in an effective manner.

Having now particularly described and ascertained the nature of my said invention and in what manner the same is to be performed, I declare that what I claim is:

1. In internal combustion engines, the combination of a compression chamber; an air inlet for the same; a vaporizing chamber provided with a fuel inlet; an obturating member separating said chambers and provided with two passages between the same; and means causing said member to slowly close and completely separate the said chambers during the suction period, to open one of said passages near the end of the compression period, and thereby admit a portion of the air compressed into the vaporizing chamber, and to then open the other passage to permit a complete admixture of fuel and compressed air; substantially as described.

2. In internal combustion engines, the combination of a compression chamber; an air inlet for the same; a vaporizing chamber provided with a fuel inlet; an obturating member separating said chambers, and provided with a large and a small passage adapted to connect said chambers; and means causing said member to slowly close the said passages, and completely separate the said chambers during the suction period, to open the smaller passage near the end of the compression period, and thereby admit a portion of the compressed air into the vaporizing chamber, and to then close the said smaller passage and open the larger passage at the end of the compression period to permit a complete admixture of fuel and compressed air, whereby a premature explosion of the said fuel is obviated, substantially as described.

3. In internal combustion engines, the combination of a compression chamber provided with an air inlet valve *a*; a vaporizing chamber provided with a fuel inlet valve *e* for the same, and a compressed air inlet valve *f*; an obturating member *h*, separating said chambers and provided with the larger passage *i*, communicating directly with the vaporizing chamber, and the smaller passage *j*, communicating with said vaporizer through the valve *f*, said passages arranged at an angle to each other, and adapted at different times to open communication between said chambers; and means causing said member *h*, to slowly close both of said passages, and completely separate the said chambers during the suction period of the engine, to open the passage *j*, near the end of the compression period and thereby admit a portion of the air compressed into the vaporizing chamber through said valve *f*, and to then immediately open the passage *i*, to per-

mit a complete admixture of fuel and compressed air, substantially as described.

4. In internal combustion engines, the combination of a compression chamber; an air inlet for the same; a vaporizing chamber; a fuel inlet for the same; a compressed air inlet for the same; a rotary obturating member provided with a larger passage permitting communication between said chambers; and a smaller passage in coöperative relation with said compressed air inlet and at an angle to said larger passage, also permitting communication between said chambers; means for operating said obturator; and a water jacket surrounding said vaporizing chamber; whereby said obturator will close communication between said chambers and

will keep the same closed during the suction period, and until near the end of the compression period, and will open the communication between said chambers, through said compressed air inlet, just before the end of the compression period, and will also open the larger passage between said chambers immediately after admitting compressed air into said vaporizing chamber, substantially as described. 20

In testimony that I claim the foregoing I have hereunto set my hand this 5th day of August 1907.

FRIEDRICH OBERHÄNSLI.
